(57) **CLAIM**

I claim the ornamental design for a top for a foldable pallet, as shown and described.

DESCRIPTION

FIG. 1 is an isometric view of a top for a foldable pallet.

FIG. 2 is a top plan view of the top of FIG. 1.

FIG. 3 is a bottom plan view of the top of FIG. 1.

FIG. 4 is a front elevation view of the top of FIG. 1.

FIG. 5 is a rear elevation view of the top of FIG. 1.

FIG. 6 is a left-side elevation view of the top of FIG. 1; and, FIG. 7 is a right-side elevation view of the top of FIG. 1.

The broken lines represent fold lines of the claimed design.

1 Claim, 5 Drawing Sheets---
